(57) **CLAIM**

The ornamental design for a fender for a vehicle, as shown and described.

DESCRIPTION

FIG. 1 is a perspective view of a fender for a vehicle, taken from the front.

FIG. 2 is a front view of the fender for a vehicle of FIG. 1. FIG. 3 is a back view of the fender for a vehicle of FIG. 1. FIG. 4 is a left-side view of the fender for a vehicle of FIG. 1.

FIG. 5 is a right-side view of the fender for a vehicle of FIG. 1.

FIG. 6 is a top view of the fender for a vehicle of FIG. 1; and, FIG. 7 is a bottom view of the fender for a vehicle of FIG. 1.

The color shown on the claimed design forms no part thereof.

The Applicant reserves the right to convert individual and various combinations of solid lines to broken lines in one or more continuation applications, since the figures convey that the inventors had possession of the features shown in solid lines, individually and in various combinations, as of the date of filing. Furthermore, Applicant reserves the right to convert the originally filed color figures to black and white line figures with appropriate shading and contour lines without the black and white line figures being considered new matter.
